UNITED STATES PATENT OFFICE.

JOHN C. THOMPSON, OF BOSTON, MASSACHUSETTS.

OVERHEAD-VALVE-SPRING COMPRESSOR.

1,405,696.

Specification of Letters Patent. Patented Feb. 7, 1922.

Application filed December 2, 1920. Serial No. 427,678.

To all whom it may concern:

Be it known that I, JOHN C. THOMPSON, a citizen of the United States, and resident of Boston, in the county of Suffolk and State of Massachusetts, have invented an Improvement in Overhead-Valve-Spring Compressors, of which the following description, in connection with the accompanying drawings, is a specification, like letters 10 on the drawings representing like parts.

My present invention relates to valve spring compressors, and more particularly to valve spring compressors for overhead valve springs on gasoline engines and the 15 like.

In removing valve stems from position in gasoline engines, it is first necessary to compress the valve spring in order to remove the holding pin that retains such spring and 20 valve stem in operative relation. With the valve arrangement employed in the ordinary gasoline engine, the above operation is a simple one, and many valve spring compressors capable of performing the compressing 25 operation have been designed. With the peculiar construction required in an engine in which overhead valves are employed, the ordinary form of spring compressor is useless, and as far as I am aware, the valve 30 spring assembly of overhead valve motors cannot be disassembled in situ with the present type of spring compressor.

With a view to obviating the objections above pointed out, I have devised the improved spring compressor which forms the subject-matter of the present application, and I am enabled, by the use of this invention, to disassemble either one valve spring 35 assembly, a battery of such valve spring assemblies, or any intermediate number of such assemblies and can perform this operation while such assemblies are in operative position in a motor.

The principal object of my invention, 40 therefore, is an improved overhead valve spring compressor for gasoline motors or the like.

Another object is the provision of an improved device of this character capable of 45 simultaneously compressing a plurality of valve springs.

Other objects and novel features of the construction and arrangement of parts constituting my invention will appear as the 50 description of the invention progresses.

In the accompanying drawings illustrating the preferred embodiment of my invention,

Fig. 1 is a sectional side elevation of the valve head of a gasoline motor, showing my 60 improved device in position, the valve spring being compressed to allow the spring pin to be readily removed;

Fig. 2 is a plan view of Fig. 1;

Fig. 3 is a view, similar to Fig. 1, but 65 with a spring compressor capable of acting on a plurality of springs simultaneously.

Fig. 4 is a plan view of Fig. 3; and

Fig. 5 is a detail of the construction shown in Figs. 3 and 4. 70

Referring to the drawings, and more particularly to Figs. 1 and 2, 10 designates a valve head, employed in motors having overhead valves, and provided with a vertically extending valve tube 11, internally threaded 75 at 12, and provided with a valve seat 13 at the junction of the said valve tube and valve head. An externally threaded valve slide 14 screws into the threads 12 and is reduced in diameter at its upper end 15 sufficient to 80 allow the valve spring 16 to loosely fit thereon, the valve spring seating on the lower end of the slide 14, as shown in Fig. 1. The valve slide is drilled longitudinally to provide a slide bearing for the valve stem 17, a 85 valve 18 formed integral with such valve stem, cooperating with the valve seat 13. The upper end of the valve stem is provided with a transverse hole 19, in which fits a pin 20, this pin 20 seating in a depression 21 in 90 the upper face of this spring seat washer 22, the lower face of this washer being formed to provide a seat for the upper end of the spring 16.

My improved device consists of a substantially rectangular frame formed of a single piece of metal preferably square in cross-section. This piece of metal is shaped as shown in Figs. 1 and 2, and has a portion 23, forming one half the handle, the portion 100 24 formed at an angle to the portion 23, a portion 25 of sufficient length to extend entirely across the valve head 10, a portion 26 at right angles to the portion 25, a portion 27 spaced apart from and lying parallel to 105 the portion 25, a portion 28 formed at an angle to the portion 27 and a portion 29 lying in engagement with and parallel to the handle portion 23. The portions 23 and 29, together form a handle, and are secured to- 110

gether with rivets 30, or in any other suitable manner. Each of the portions 25 and 27, adjacent the portion 26, is drilled to provide a holding means for a hook member 31, to which is suspended a chain 32, or other suitable flexible member, and to the lower end of this chain 32 is attached a hook 33, the free end of which is adapted to engage the surface 34 of the valve head 10.

10 The manner in which this device operates will be obvious from an inspection of Figs. 1 and 2, and it will be noted that the portions 25 and 27 are spaced apart sufficiently to allow the pin 20 to pass between them, 15 while they are sufficiently close to each other to ensure firm engagement with the washer 22.

20 Referring now to Figs. 3, 4 and 5, where like parts of the engine that are similar to parts shown in Figs. 1 and 2 have been designated by the same reference numerals, I have shown my improved device as adapted to operate on a battery of valve springs simultaneously. This method of operation is desirable where much work of this character is done, as it obviates the necessity of a workman performing a multiplicity of operations.

25 My improved device consists of two parallelly arranged bars or rods 35 and 36, having their ends reduced in diameter and threaded to receive end bars 37 and 38, held in position by nuts 39. Each of the end bars, as shown in Fig. 5, is provided with 30 a slot 40 in which is slidably mounted bearing members 41 held in adjusted position by set screws 42 passing through the body of the members into the slot 40. These bearing members 41 are drilled to receive the reduced ends of the bars 43, these bars being 35 non-circular and preferably square in cross-section. On the rod 36 I attach a pair of hook members 44, the lower ends of which are bent to engage with the surface 34 of the valve head. While I have shown two 40 of the hook members 44, it is obvious that I may employ more, as three, four, or one for each cylinder of the motor. With this construction, it is obvious that I may adjust 45 the bars 43 relatively to each other to operate on motors in which the spring washer 50 22 varies in diameter.

55 While I have shown and described the preferred embodiment of my invention somewhat in detail, it is to be understood that I may vary the size, shape and arrangement of parts constituting my improved de-

vice within considerably wide limits without departing from the spirit of the invention.

60

My invention is further described and defined in the form of claims as follows:

1. An improved overhead valve spring compressor for use with gasoline motors and the like comprising a handle, a pair of parallelly arranged members attached to said handle, and spaced apart from each other, a member attached to said parallelly arranged members and at the end thereof remote from the handle, and a hook attached to the free end of said member.

65

2. An improved overhead valve spring compressor for use with gasoline motors and the like comprising a handle, a pair of parallelly arranged members spaced apart from each other, and formed integral with each other and with the handle, a member attached to said parallelly arranged members and at the end thereof remote from the handle, and a hook attached to the free end of said member.

75

3. An improved overhead valve spring compressor for use with gasoline motors and the like comprising a frame, including parallelly arranged bars, end members attached to said bars, hook members attached to one of said parallelly arranged bars, and means attached to the end members for engaging with the spring holding washers of a gasoline motor.

85

4. An improved overhead valve spring compressor for use with gasoline motors and the like comprising a frame including parallelly arranged bars, end members attached to the said bars, hook members attached to one of said parallelly arranged bars, and adjustable means attached to the end members for engaging with the spring holding washers of a gasoline motor.

90

5. An improved overhead valve spring compressor for use with gasoline motors and the like comprising a frame, including parallelly arranged bars, end members attached to the said bars, hook members attached to one of said parallelly arranged bars, a slot in each end member, a pair of bearings in each slot, and adjustable with respect to each other, a pair of bars spaced apart from and parallel to each other mounted in said bearings, and means for holding said bearings and bars in adjusted position.

100

In testimony whereof, I have signed my name to this specification.

JOHN C. THOMPSON.
